METHOD OF AND APPARATUS FOR LOCATING SIGHTS ON GUN-BARRELS.

1,180,886.

Specification of Letters Patent. Patented Apr. 25, 1916.

Application filed June 12, 1915. Serial No. 33,853.

To all whom it may concern:

Be it known that I, ELWYN T. STEPHENS, a citizen of the United States, residing in Springfield, Hampden county, Massachusetts, have invented new and useful Improvements in the Method of and Apparatus for Locating Sights on Gun-Barrels.

In the art of manufacturing rifles it becomes necessary among other things to properly locate the sights so that all projectiles will be directed toward the object upon which the arm is sighted. It is a well known fact that it is not practicable and rarely possible to produce a rifle barrel 10 wherein the bore is perfectly straight from end to end. It is also known that the projectile follows the direction imparted to it by the first two or three inches of the bore at the muzzle end of the barrel. 15 The common term for properly locating the sights on a rifle barrel is "targeting" and it is to be understood that in using that term reference is made to properly locating the sights so that when the rear sight is set 20 on the zero mark the bullet will be directed toward the object sighted upon.

The present method of "targeting" a gun or locating the sights is to attach the rear sight locating the zero line in the center of 25 the bore, then adjustably mounting the front sight and test the rifle by shooting at a target and moving the front sight to the left or right as the case may require, after each shot until the desired position is found or 30 in other words, until the center of the target is pierced by the bullet when sighted, and the rifle is then considered to be properly sighted or targeted.

It is commonly found necessary to fire a 35 rifle a considerable number of times, thus causing loss of time and ammunition. Now while such "targeting" may properly establish the location of the sights for one distance, it leaves them improperly located for 40 any other distance unless it should happen that the bore is absolutely straight and that the front and rear sights are both located directly over the axis of the bore. This, however, probably in 99 per cent. of the instances 45 is not possible, so that as a result the front sight is rarely located over the axis of the bore of the first two or three inches at the muzzle end, so that if the rifle be targeted so that the bullet will strike the 50 center of the bull's-eye at 200 yds. (this being the common distance for military or

service rifle test) the bullet will not strike the center of the bull's-eye at 300, 400 yards or at any distance other than that for which it was targeted. It is also common in the 55 locating of the sight on a rifle barrel to work from the outside upon the assumption that the bore is parallel in alinement with the interior of the barrel. It will now be seen that if the bullet is controlled in its 60 direction by the center line of the muzzle portion of the bore the gun, in order to be properly sighted, should have the front sight located directly above such center line and that the zero line of the rear sight 65 should be located in perfect alinement or in the same vertical plane as the center line of the muzzle end of the bore and that, therefore, the front sight should be first accurately located directly above such center line 70 and the necessary location of the zero line of the rear sight ascertained.

When the front and rear sights are located as above stated the gun will have been 75 properly "targeted" so that no firing or change of adjustment of the sights is required.

As a means for accomplishing the desired result and as one means of exemplifying my invention I show an apparatus in the 80 accompanying drawings wherein the direction of the bore at the muzzle end of the barrel is ascertained and from this point means are employed to locate the zero line 85 of the rear sight so that the front sight and the zero line of the rear sight are in perfect alinement with and in the same vertical plane as the center line of the muzzle end of the bore.

In the accompanying drawings in which 90 like letters of reference indicate like parts: Figure 1 is a side elevation of a mechanism devised by me as one means of carrying out my invention. Fig. 2 is a plan view of the same. In these two figures the barrel is 95 shown in Fig. 1 and is omitted from Fig. 2.

In this apparatus I may employ a suitable member comprising a perfected straight rod which I term the "plug" and which has a close sliding fit in the muzzle end of the barrel. The portion of this plug which projects beyond the muzzle enters with a close sliding fit a suitable member projecting vertically therefrom and firmly secured to said vertical member is an arm or bar of sufficient length to extend to the rear portion of the barrel and I prefer that one face of such 100 105 110

arm or bar be in perfect alinement with the axis of the plug so that if a marking tool be placed against this face and moved downwardly against the barrel at the point where the rear sight is to be located the location of the zero line of the rear sight may be ascertained and this being properly marked may be relied upon in locating the rear sight so that when it is set at the zero mark it will be in perfect alinement with the axis of the muzzle end of the bore. Explaining now the details of construction of said apparatus as illustrated in the drawings, I prefer that for convenience in supporting the gun while ascertaining the proper location of the zero line for the rear sight, to provide a supporting mechanism comprising a suitable base as *a* having uprights *b* and *c*. The uprights *b* are provided with adjusting screws *d* adapted to bear against the side of the front sight. It is desirable that the forward sight be permanently fixed to the barrel in the same vertical plane and in alinement with the axis of the bore at the muzzle end and this sight being fixed in position, the end of one of the adjusting screws *d* being brought to a position which when one side of the sight bears against it, will bring the center line of the sight in the same plane as the center line or axis of the bore, it simply becomes necessary to set up the other adjusting screw until it bears against the sight on the opposite side and thus rotate the barrel until both sides of the sight are in contact with the adjusting screws. The barrel will then be properly located with reference to the front sight being in the same vertical plane as the axis of the bore at the muzzle end. I prefer that the upright *c* be provided with a laterally movable table *e* suitably supported to ride upon anti-friction mechanism which in the drawing I illustrate as rolls *f*. It will now be seen that when the gun is placed in position, the portion toward the stock resting upon the table *e* may be moved laterally with perfect ease. In Fig. 1 of the drawing I show the barrel marked *g* and a portion of the stock marked *h*. If the barrel and stock be now placed in position and the plug *i* inserted through the opening in the block *j* into the bore of the barrel at the muzzle end, the barrel will be immediately brought into proper alinement without difficulty because of the lateral movement growing out of the employment of the anti-friction table supporting mechanism. The block *j* is provided with a lower extension *k* pivotally mounted in the part *l* which latter is pivotally mounted in the base *a*. The block *j* has firmly attached to it, the straight edge extension *m*, one face of which is in perfect alinement with the axis of the portion of the plug *i* which enters the muzzle end of the bore. The extension *m* has mounted upon it a slid-

ing member *n*, provided with a marking tool *o*, capable of vertical movement, so that when the plug is properly inserted at the muzzle end of the barrel, the marking tool *o* may be moved toward the barrel and the zero mark for the rear sight, and thus mark in the proper position so that it will be in perfect alinement or in the same vertical plane as the axis of the bore at the muzzle end of the barrel. In order to avoid danger of possible friction, and give the extension *m* perfect freedom of movement, I prefer that its free end be supported on a suitable table, the latter being supported by anti-friction mechanism and for this purpose I have shown a table *p* on anti-friction rolls *r* the latter being supported by a suitable member *s* secured to the base *a*.

In order to adapt the apparatus for guns of different size bore, I prefer that the block *j* be provided with a bushing through which the plug passes and it will readily be seen that bushings of the same exterior diameter but of different interior diameter may be employed with the same block.

It will readily be seen that the method of ascertaining the location of the zero line for the rear sight invented by me, may be employed without the supporting apparatus illustrated in the drawings, although I deem this, as at present advised, the most convenient apparatus for the purpose. It will also be seen that very many modifications may be made without departure from my invention and I do not wish to be understood as limiting my claim to the specific mechanism herein explained for ascertaining the proper location of the zero line of the rear sight, or in other words, the "targeting" of a gun barrel.

It will readily be seen that if the gun be sighted or "targeted" so that a bullet will strike the center of the bull's-eye at a 200 yard range, the "targeting" being carried out in the old way, that is, by firing the gun and moving the front sight until the bullet strikes the center of the bull's-eye, that unless the bore be perfectly straight from end to end the arm will not be accurate at any range and that while the difference in accuracy at a distance nearly approximating 200 yards may be said to be trifling and microscopic, it will also be seen that at a range of a mile or more, or at the extreme limit of the carrying capacity of the arm, such inaccuracy is likely to be serious. It will also be seen that the old method of "targeting" guns comprising firing and adjusting the forward sight is tedious and expensive and the accuracy as to the range of test is largely dependent upon the personality of the person making the test and that by the old method the targeting relates only to one distance.

So far as known to me, no means has here- 130

tofore been provided by which the zero or proper mark for the center line of the rear sight has been scientifically or mechanically ascertained.

5 Having therefore described my invention, what I claim as new and desire to secure by Letters Patent, is,—

10 1. The method herein described of "targeting" gun-barrels, the same comprising first locating the front sight in the same vertical plane with the axis of the bore at the muzzle end of the barrel and then locating the zero line for the rear sight in perfect alinement with the vertical plane of the 15 axis of the bore at the muzzle end of the barrel.

20 2. The improvement in the art of "targeting" gun-barrels, comprising first ascertaining the direction of the bore at the muzzle end of the barrel, locating the position of the front sight above and in line with the axis of such bore, ascertaining the position of the vertical plane of the axis of such bore when extended to the heel portion of 25 the barrel and locating the zero mark for the rear sight at such point whereby the front and rear sights are in the same vertical plane with the axis of the bore at the muzzle end of the barrel.

30 3. An apparatus for properly locating the zero mark of the rear sight of a gun-barrel, comprising a plug adapted to fit and to be inserted in the muzzle end of a gun-barrel and to project therefrom and means sup- 35 ported by the projecting portion of such plug extending vertically and rearwardly by which the vertical plane of the axis of the bore of the muzzle end may be located on the rear portion of the barrel, substantially 40 as shown.

4. In an apparatus of the class described means to ascertain the alinement of the bore of the muzzle end of a barrel, a member con-

nected therewith adapted to support a straight edge and a straight edge member 45 extending to the rear of and outside of the barrel, one edge of said straight-edge being adapted to be arranged in alinement with and in the same vertical plane with the axis of the bore of the muzzle end of the barrel 50 and a marking member adapted to mark such line at the rear of the barrel.

5. In an apparatus for "targeting" gun barrels, the combination of a suitable support for a gun barrel, a rigid member adapt- 55 ed to enter and fit the bore at the muzzle end of a gun barrel and to extend in direct line therefrom, a member mounted, supported by and projecting vertically from the first member, a member rigidly secured to the 60 latter member and adapted to extend to the rear portion of the barrel and anti-friction means carried by the supporting frame for supporting the rear portion of the barrel substantially as shown. 65

6. In an apparatus of the class described, the combination of a suitable support for rigidly supporting a gun barrel, means controlled by the wall of the bore at the muzzle end to ascertain the direction of the bore of 70 the muzzle end of the barrel, and means, co-operating therewith and extending therefrom to locate the vertical plane of the axis of such direction at the rear portion of the barrel. 75

7. In an apparatus of the class described the combination of a member adapted to enter and bear against the wall of the bore of a gun barrel at its muzzle end, and means co-operating with and controlled by the first 80 mentioned member to locate a point on the exterior of the rear portion of the barrel in the vertical plane of the axis of the bore of the muzzle end, substantially as shown.

ELWYN T. STEPHENS.
